UNITED STATES PATENT OFFICE

162,136

AUTOMOBILE

Harley J. Earl, Grosse Pointe Farms, Mich., assignor to General Motors Corporation, Detroit, Mich., a corporation of Delaware

Application June 25, 1949, Serial No. 3,538

Term of patent 7 years

(Cl. D14—3)

To all whom it may concern:

Be it known that I, Harley J. Earl, a citizen of the United States, and a resident of Grosse Pointe Farms, county of Wayne, State of Michigan, have invented a new, original, and ornamental Design for an Automobile, of which the following is a specification, reference being made to the accompanying drawing, forming a part thereof.

In the drawing:

Figures 1 and 2 are perspective views of an automobile showing my new design.

Figure 3 is a fragmentary plan view thereof.

Figure 4 is a fragmentary side elevational view.

Figure 5 is a fragmentary rear view.

The dominant features of my design are shown in solid lines.

I claim:

The ornamental design for an automobile, substantially as shown and described.

HARLEY J. EARL.
